[57] CLAIM

The ornamental design for a cotton candy machine, as shown and described.

DESCRIPTION

FIG. 1 is a top, front and right side perspective view of a cotton candy machine showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side being a mirror image of the right; and

FIG. 7 is a sectional view thereof on an enlarged scale taken on line 7—7 of FIG. 2.

FIG. 1

FIG. 2

FIG. 3

FIG. 4

FIG. 5

FIG. 6

FIG. 7
